**DUST COVER FOR THE RELAY PORTION OF
AUTOMATIC TELEPHONE SWITCHBOARDS**

Joseph F. Becker, Sr., Topeka, Kans.

Application June 28, 1954, Serial No. 31,183

Term of patent 3½ years

(Cl. D26—1)

Fig. 1.

Fig. 2.

Fig. 3.

Fig. 1 is a front perspective view of a dust cover for the relay portion of automatic telephone switchboards, showing my new design.

Fig. 2 is a rear perspective view thereof; and

Fig. 3 is a top plan view of the dust cover for the relay portion of automatic telephone switchboards.

I claim:

The ornamental design for a dust cover for the relay portion of automatic telephone switchboards, as shown.
